[57] **CLAIM**

The ornamental design for caliper brake housing, as shown.

DESCRIPTION

FIG. 1 is a top perspective view of a caliper brake housing showing my new design;
FIG. 2 is a front view of the present invention;
FIG. 3 is a rear view of the present invention;
FIG. 4 is a left side elevational view of the present invention;
FIG. 5 is a right side elevational view of the present invention;
FIG. 6 is a top plan view of the present invention;
FIG. 7 is a bottom perspective of the present invention; and,
FIG. 8 is a cross sectional view taken along line 8—8 in FIG.
2 of the present invention.
